UNITED STATES PATENT OFFICE.

JACOB FRANZMANN, OF CINCINNATI, OHIO, ASSIGNOR OF ONE-HALF TO
HENRY VARWIG, OF SAME PLACE.

BUNG CUTTING AND COMPRESSING MACHINE.

SPECIFICATION forming part of Letters Patent No. 254,298, dated February 28, 1882.

Application filed May 12, 1881. (No model.)

To all whom it may concern:

Be it known that I, JACOB FRANZMANN, of the city of Cincinnati, county of Hamilton, State of Ohio, have invented certain new and 5 useful Improvements in Bung Cutting and Compressing Machines, of which the following is a specification.

This invention relates to machines for making bungs. Its object is to rapidly and smoothly cut what is known as "flat bungs," and to compress the same into the proper shape, stamping them at the same time with a name, card, or trade-mark.

In the accompanying drawings, forming part 15 of this specification, in which similar reference-letters indicate identical parts in the various views, Figure 1 is a view taken in front of one end of my machine, showing the mechanism for compressing, stamping, and discharging the bungs. A portion of the box for feeding the blanks to the hollow cutter is broken out to expose the screw-plunger and adjustable interior guides. One of the front standards is also broken off to show the compressing-plunger 20 and the stationary die in vertical section. Fig. 2 is an enlarged end view of the frame in which is mounted the compressing mechanism. The plunger and its guides are shown 25 in vertical section. The feeding devices in this view are removed. Fig. 3 is a top plan view of the mechanism for feeding the bungs to the compressing and stamping dies. Fig. 30 4 is an axial section of the compressing-die greatly enlarged. Fig. 5 is a similar view of the stationary die and name-stamp. Fig. 6 is a longitudinal central section of the end of the screw-plunger for feeding the blanks and 35 forcing them through the hollow cutter. Fig. 7 is an axial section of the cog-wheel and nut 40 by which the screw-plunger is driven. Fig. 8 is a top plan view of the head-stock, the plunger-driving mechanism mounted therein, and part of the boxes through which the bung-blanks are fed to the cutters. Fig. 9 is a longitudinal horizontal section of the end of one 45 of the feed-boxes. Fig. 10 is a vertical longitudinal section of the same, and Fig. 11 is a transverse vertical section through line $x-x$ of Fig. 9.

50 The compressing mechanism is mounted in

a strong frame composed of four upright standards, A, made preferably of cast-iron, framed together by iron cross-braces. This frame is to be firmly secured to the floor or foundation and braced at the top to the timbers of the building. Secured to the front of this frame is an open-top cast-metal box, B, both ends of which extend beyond the frame. One end is secured to the frame C, which supports the mechanism by which screw D is alternately driven through the trough B and a similar trough which extends in the same plane from the opposite side of frame C. In each outer end of boxes B are secured hollow cutters E. The axes of the cutters are in the same plane as the axis of screw D. The edges of the cutters are sharpened back upon opposite sides, leaving two opposite projecting points, so as to give a drawing cut as the square blanks are forced through the cutters. 70

Within trough B are three metal guide-strips, F, which have fins projecting through slots in the walls of box B. These strips are adjusted at equal distances from the axis of screw D to receive the blank to be cut, and are held in the desired position by set-screws tapped through or into bosses which are cast upon the exterior walls of box B. The bung-blanks, which are square blocks of the proper size to form the bungs, are placed on edge in the space formed by the strips F, and are held down by a hinged latch, f''. The screw D is driven by a nut, G, upon which is keyed a cog, H. This cog meshes into and is driven by a cog, I, secured upon the driving-shaft J. Upon the driving-shaft are four pulleys, the two outside ones being loose and the inner ones keyed to the shaft. The shaft is driven alternately in opposite directions, as a cross or straight belt from the same main shaft is shipped onto one or the other of the tight pulleys. The screw is by this means advanced alternately in the direction of each of the hollow cutters fixed in the opposite ends of the box B. To avoid driving the screw D against the cutters E, the belts are automatically shipped upon the loose pulleys when the screw has reached the limit of its stroke in either direction by cross-pieces d, which are secured upon each end of screw D, and extending across the box B are guided 90 95 100

upon its walls. As the screw travels nearly the limit of its stroke in one direction the piece *d* upon its opposite end strikes the downward-projecting end of one of the belt-shippers 5 *K*, throws the belt upon the loose pulley, and stops the machine. Upon each end of the screw *D* is secured a hard wood shaft, *d'*. These are detachable and are to be changed to correspond with the different-sized bungs and the different-sized cutters through which pieces *d'* pass to discharge the bungs through the hollow cutters and into receiving-tubes *L*, which are placed in line with the cutters and opposite their discharge ends.

15 The operation of the cutting part of my machine is as follows: Square blocks, of the requisite size to form bungs, are cut from strips, a number of which are held with their flat sides together and fed to a crosscut-saw, the blanks 20 passing as they are severed into a sheet-metal trough suitably placed to receive them. The trough should be of a size to contain enough blanks to nearly fill the space within guide-strips *F* between the retracted screw and the 25 cutter *E*. The screw being now, for instance, in the right-hand end of box *B*, the hinged bar *f''* above the left-hand box *B* is thrown up, and one end of the trough containing the bung-blanks is slipped under it with the end blank 30 against the hollow cutter and the trough in an inclined position above the lower strip *F*. Now, by pressing the blanks in the direction of the cutter with one hand the trough is withdrawn with the other, leaving the blanks on 35 edge within the space between the feed-strips. The bar *f''* is now lowered upon the row of blanks and secured by the latches *f³*, which are turned over it and buttoned by the *T*-catches *f⁴*. The blanks are placed between the guides 40 with the grain of the wood running horizontally across the feed-box, and the points of the cutter *E* are vertically opposite each other, so that the corners of the blanks are trimmed off with drawing cuts. When the machine is 45 started the blanks are forced through the hollow cutter by screw *D* into the receiving-tube *L*. During this operation the opposite box *B* is being supplied with blanks in the manner above described, so that when the belt is shipped 50 upon the loose pulley by cross-piece *d'* the other belt may be run onto its tight pulley and the screw-plunger driven in the opposite direction, forcing the blanks through the opposite cutter.

The mechanism to compress the cylindrical 55 bung-blanks into the conical-shaped bung and to stamp them with the name of the manufacturer or user will now be described.

The hollow compressing-die *M* is secured in the lower end of a hollow plunger, *N*, which is 60 driven by a pitman, *O*, actuated by an eccentric secured upon the shaft *P* in the upper part of the machine-frame.

The stationary die *Q* occupies a circular cavity in table *R*, which is vertically adjustable between standards *A*.

65 The stationary die, Fig. 5, has an annular

groove, *q*, to receive the lower end of the die *M*, and a central depression to receive the name-die *q'*, which is loosely dropped into it. By this arrangement the same letter-die may 70 be used for several sizes of bungs.

75 *S* are slides tongued upon the edges to enter grooves in the guides *S'*, which are supported upon angle-pieces *S''*, which are vertically adjustable by means of set-screws and slots on the cross-braces, which extend between the uprights *A*. To these slides are secured frames *s*. These frames extend beyond the uprights *A*, and have centrally secured to their center cross-pieces pushers *s'*, which extend inward 80 upon the die-table *R*. The slides and their frames are actuated through levers *V* by cams *T*, secured upon shaft *P*. Springs *Y* hold the upper ends of the levers in contact with their cams and return the slides to the position 85 shown, Fig. 3, after the blank has been pushed from the bottom of the tubular socket above the die *Q*.

Within the hollow plunger *N* is a rod, *n*, the upper end of which is screwed through a cross-piece which is secured to the frame of the machine, and passes through the bifurcated end of the pitman. The rod extends through the hollow plunger and to near the end of the compressing-die *M*, for the purpose of discharging 95 the compressed bung from the die at the upward stroke of the die and plunger.

Two springs, *W*, are secured upon table *R*. The curved fingers of these springs occupy positions upon each side of the stationary die 100 and stop the bung-blanks in position to be acted upon by the dies. The upper edges of the springs flare outward to permit the die *M* to pass down between them, expanding the fingers after the die has commenced its action 105 upon the blank. The table *R* and slide-carriers *S'* are adjusted to the same height for the purpose of compressing bungs of different thicknesses. The rods *U* have their fulcrums on pins in cross-piece *u*. The fulcrum-pins 110 pass through slots in the levers, so that they may be also elevated or lowered with the slides *S*.

The operation of this part of my machine is as follows: The tubes *L*, which have been filled with circular blanks from cutters *E*, are placed 115 in sockets *L'* upon each side of the machine, and pins which had been passed through the lower end of the tube to retain the blanks are withdrawn, letting the blanks drop down through the sockets *L'*, the lower blank resting upon the 120 table *R* below the socket, the lower end of which is a little more than the thickness of a bung above the table. The pusher *s*, as the slide is drawn toward the center of the machine, pushes the lower blank into the bite of fingers *w* above 125 the die *Q*. As the pusher is withdrawn by spring *Y* from beneath the socket *L'* another bung-blank drops upon the table. In the meantime the die has been forced down and the first blank compressed and stamped. As the next 130 blank is carried above the die *Q* the first is pushed off and discharged through an open-

ing in the table. The operation continues until the tube L is empty, (which fact can be observed through the slot in the side of the tube,) when it can be exchanged for a filled tube before the blanks remaining in the socket are all compressed. Thus the operation of the machine is continuous.

Instead of the screw-plunger shown, a rack and pinion may be substituted; and if it is only desired to cut bungs of one size of the same diameter the interior adjustable strips, F, may be entirely dispensed with.

What I claim is—

1. The combination, substantially as before set forth, of the elongated covered feed-box adapted to receive a number of blanks at a time, the stationary hollow cutter secured at the end thereof, the elongated plunger or follower, and a screw to feed the follower through the box for the purpose of forcing the square blanks through the hollow cutter.

2. The combination of two elongated covered feed-boxes arranged upon each side of a plunger-driving mechanism and adapted to receive a number of blanks at a time, the stationary hollow cutters fixed at the opposite ends of said feed-boxes, with the elongated follower D, and a screw to alternately drive said follower from one of the boxes into the other, substantially as specified.

3. In a bung-machine of the character described, the combination of two feed-boxes, B, the plunger-driving mechanism mounted in frame C centrally between the said boxes, with the plunger D, and cross-pieces d, secured to the plunger near each end thereof, and the shippers K, having projections in position to be acted upon by the cross-pieces d, to automati-

cally stop the mechanism when the plunger has reached the limit of its stroke, substantially as specified.

4. The combination, substantially as hereinbefore set forth, of feed-box B, hollow cutter E, secured at the end thereof, with the screw-follower D, nut G, and driving-wheel H, keyed upon said nut, for the purpose set forth.

5. In a machine for cutting bungs, the combination, substantially as specified, of box B, follower D, changeable hollow cutter E, and the adjustable guide-strips F, to adapt the machine to feed and cut different sizes of bungs.

6. The combination, substantially as before set forth, of the elongated open-top feed-box adapted to receive a number of blanks at a time, the elongated plunger, and suitable mechanism to feed the same back and forth through said box, and the hollow cutter arranged at one end of said box, with the hinged bar f' adapted to be elevated for the purpose of supplying the box with blanks, and to be secured upon said blanks to prevent them from being forced up by the plunger as said blanks are fed to the hollow cutter.

7. The combination, substantially as specified, in a bung-machine, of the reciprocating hollow plunger N, fixed rod n, compressing-die M, and fixed die Q, having the annular groove q, with feeding mechanism consisting of a sliding frame, s, pusher s', actuated by cams T and levers V, and the spring-fingers W, to hold the blanks until acted upon by the compressing-die.

JACOB FRANZMANN.
